S. L. JOINER

CENTRIFUGAL DIRT COLLECTOR

Filed April 7, 1926

Inventor;
Sylvester L. Joiner;

By

John W. Johnson

Atty.

UNITED STATES PATENT OFFICE.

SYLVESTER L. JOINER, OF MCGREGOR, TEXAS.

CENTRIFUGAL DIRT COLLECTOR.

Application filed April 7, 1926. Serial No. 100,465.

The invention relates to a centrifugal dirt collector for air brake systems.

The object of the present invention is to improve the construction of centrifugal dirt collectors and to provide a simple, practical and efficient dirt collector of strong, durable and inexpensive construction designed to be applied to air brake systems of railway cars and capable of enabling the same to have the dust and dirt and other foreign matter easily and quickly removed from the dirt collectors without cutting out a car from a train and without necessitating overhauling the car.

15 A further object of the invention is to provide a centrifugal dirt collector of this character adapted to permit the accumulated dust and dirt to be instantly discharged at any time while the car is not in motion and 20 from the side of the car without the use of any tools.

Another object of the invention is to enable the present improvements to be readily applied to the centrifugal dirt collectors 25 in present use on railway cars without removing or discarding the main casing or body containing the dust separating and collecting chambers as well as to be applied to new railway cars.

30 With these and other objects in view, the invention consists in the construction and novel combination and arrangement of parts hereinafter fully described, illustrated in the accompanying drawings and pointed out in the claims hereto appended, it being understood 35 that various changes in the form, proportion and other minor details of construction, within the scope of the claims, may be resorted to without departing from the spirit or sacrificing any of the advantages of the 40 invention.

In the drawings:

Figure 1 is a central vertical sectional view of a centrifugal dirt collector constructed in accordance with this invention and adapted to be applied to new cars.

Fig. 2 is a detailed perspective view of the deflecting guard with its supporting posts.

Fig. 3 is a central vertical sectional view 50 illustrating a modification of the invention for adapting the same to be applied to cars equipped with the Derby dirt collector.

Fig. 4 is a horizontal sectional view on the line 4-4 of Fig. 1.

55 In the accompanying drawing in which is illustrated the preferred embodiments of the

invention 1 designates a dirt collector casing designed to be applied to new cars and comprising an upper downwardly tapered funnel shaped dust separating or precipitating 60 chamber 2 and a lower substantially cylindrical dust collecting chamber 3. The casing is provided at the top with an inlet 4 and an outlet 5 which is provided at the inner end with a depending conduit 6 extending 65 downwardly into the dust separating chamber 2 and forming an annular passage between it and the walls of the upper portion of the dust separating chamber. The centrifugal dirt collector, which may be 70 arranged in an air brake system at any desired point is usually placed between the triple valve and the brake pipe and air passing from the brake pipe to the triple valve enters the separating chamber in a comparatively narrow stream, the direction of the stream or current being slightly downwardly inclined to one side of the outlet pipe whereby the air discharges into the separating 75 chamber past said pipe. Thus the stream 80 or current of air tends on entering the chamber 2 to pursue a spiral course to a plane at least somewhat below the mouth of the outlet pipe or conduit 6. A constant change 85 of angle of the stream of air causes any particles of dust or dirt carried by the air to strike against the circular wall of the separating chamber 2 and be deflected thereby in a downward direction. The entire body 90 of air in the chamber 2 will of course be in motion during the passage of the direct current from the inlet to the outlet, but the large capacity of the chamber 2 as compared with the area of the inlet and outlet ports causes the velocity of the current to be 95 greatly diminished while passing through the chamber, and the movement of the air will be with decreasing force towards the lower end of the said chamber 2. Thus the particles of dust deflected downward move 100 further and further away from the direct influence of the main air current and descend by gravity until they fall into the collecting chamber 3. In falling into the collecting chamber, the particles of dirt and dust pass downward beneath a deflecting guard 7 located within the upper portion of the dust collecting chamber and consisting of a disk having a convex or slightly rounded upper face and a substantially flat lower face. The 105 disk which is of slightly greater diameter than the mouth or entrance of the dust col-

lecting chamber forms a guard or shield for preventing the dust after entering the collecting chamber from passing upward out of the same so that the dirt and dust falling 5 into the collecting chamber will be securely trapped therein and will be retained in the dust collecting chamber until discharged through a drain cock 8. The deflecting guard is supported at diametrically opposite 10 points by parallel vertical posts 9 which are spaced apart to provide a clear passage through a bottom outlet opening 10 which is controlled by the drain cock 8. The supporting posts which are preferably straight 15 are located beyond and out of line with the outlet opening at the bottom of the collecting chamber so as not to interfere with the free discharge of the dirt and dust. By this construction a relatively large tubular outlet or discharge opening is provided for the 20 passage of the dust and dirt and the latter may be readily removed by simply opening the drain cock 8. The drain cock 8 may be of any desired construction and it is provided at one end with an operating handle 25 and is preferably backed at the other end by a nut 12, a coiled spring 13 being interposed between the nut and the valve member of the drain cock for maintaining a tight 30 connection and to effectually prevent any leakage of the air. The chamber or transverse opening 14 which receives the valve member of the drain cock may be bushed as shown but the drain cock may be constructed 35 in any other desired manner as will be readily understood.

When the invention is to be applied to cars equipped with the Derby dust collector the plug carrying the deflector is removed 40 from the lower end of the casing and a sleeve 15 is substituted for the same. The sleeve is threaded at its upper portion at 45 to screw into the lower end of the casing and it has formed integral with it upwardly extending posts 17 constructed similar to the posts heretofore described and supporting a disk 18 constituting a deflecting guard. The disk 18 is similar in construction to the disk heretofore described and operates in a 50 similar manner as will be readily understood. The lower portion of the sleeve or tubular member 15 is exteriorly threaded and receives a drain cock 19 constructed similar to that heretofore described. The form 55 of the invention illustrated in Fig. 3 of the drawing operates in exactly the same manner as the form illustrated in Fig. 1 and a relatively large unobstructed outlet or discharge passage is provided for the removal of the 60 accumulated dust and dirt. The drain cock is adapted to be operated from the side of the car at any time when the car is stationary and it may be opened without the use of any tools and the accumulated dust and dirt 65 will be instantly discharged. The removal

of the dust and dirt will not require a car to be cut out of a train and it will also be unnecessary to frequently overhaul cars for the purpose of removing accumulated dust from the dust collectors. Also the ready removal of the dust by means of the drain cock will avoid the damage which oftentimes results from the dust and dirt accumulating in the dust collector and after filling the dust collector being carried to and filling the 70 openings of the screen or strainer of the triple valve and causing the latter to be blown into the triple valve. This has frequently happened necessitating the removal of the triple valve from the car and the taking apart of the triple valve in order to remove particles of the wire of the strainer 75 from the mechanism.

What I claim is:

1. A centrifugal dirt collector for air 85 brake systems comprising a casing having an upper dust separating chamber and a lower dust collecting chamber provided at the bottom with a central tubular outlet forming a discharge opening for the dust, a drain cock 90 for controlling the discharge of the dust through the said outlet, and a substantially horizontal deflecting guard located in the upper portion of the dust collecting chamber below the mouth or inlet opening of the 95 same and being of greater diameter than the mouth or inlet and provided with supporting means located beyond and out of line with the discharge opening so as not to obstruct with the free passage of the dust and 100 dirt into the same, said guard permitting the dust to be discharged from the dust collecting chamber without removing the guard therefrom.

2. A centrifugal dust collector for air 105 brake systems comprising a casing having an upper dust separating chamber and a lower dust collecting chamber provided at the top with a reduced mouth or inlet and having a tubular outlet at the lower end 110 forming a discharge opening, a horizontally disposed deflecting guard located in the upper portion of the dust collecting chamber below the mouth or inlet thereof and being of greater diameter than the said mouth or 115 inlet and spaced posts supporting the deflecting guard and connected therewith at substantially diametric points, said guard permitting the dust to be discharged from the dust collecting chamber without remov- 120 ing the guard therefrom.

3. A centrifugal dust collector for air 125 brake systems comprising a casing having an upper dust separating chamber and a lower dust collecting chamber and provided at the bottom thereof with an opening, a tubular member secured in the opening in the bottom of the lower chamber and provided with upwardly extending posts arranged within the 130 said lower chamber, a substantially horizon-

tal deflecting guard supported by the said posts and located below the upper end of the said lower chamber, said tubular member forming an unobstructed dust discharge opening insertable through the bottom opening of the dust collecting chamber, and a drain cock carried by the tubular member

for controlling the discharge of dust and dirt without removing the guard from the dust collecting chamber.

In testimony whereof I have hereunto set my hand.

SYLVESTER L. JOINER.
